UNITED STATES PATENT OFFICE.

GEORGE W. WALKER, OF MALDEN, MASSACHUSETTS.

GRATE.

SPECIFICATION forming part of Letters Patent No. 412,570, dated October 8, 1889.

Application filed January 10, 1889. Serial No. 296,013. (No model.)

To all whom it may concern:

Be it known that I, GEORGE W. WALKER, of Malden, county of Middlesex, State of Massachusetts, have invented an Improvement in 5 Grates, of which the following description, in connection with the accompanying drawings, is a specification, like letters on the drawings representing like parts.

This invention in grates is an improvement 10 upon the grate shown and described in United States Patent No. 362,063, and has for its object to improve the construction of the same, whereby a stronger and more efficient grate is obtained.

15 In accordance with my invention the central section of the grate consists of a casting composed, preferably, of two longitudinal bars or webs united at intervals by cross-bars to leave central air-spaces, the said longitudinal bars or webs being provided at their outer side with projections which co-operate with fingers on the side bars or agitators. Each side bar is made with a deep longitudinal web, from which project fingers, and each 20 finger at its junction with the web is made of substantially the same width as the web, the said finger being made tapering from the said web toward its end. In this manner a very strong side bar is produced from a minimum 25 amount of metal, whereby increased strength is obtained and warping of the said side bars obviated. Each side bar may be provided with a locking projection on its rear side or on its under side, substantially in line with 30 the journal. The bed-plate is provided at its front and rear sides with orifices through 35 which the journals of the central section are extended, so that when the said section is placed in position it cannot be accidentally 40 dislodged or unlocked from its operative position by vertical movement of the grate, while at the same time the grate-bars may be removed without disturbing the lining.

The particular features in which my invention consists will be pointed out in the claims at the end of this specification.

Figure 1 is a top or plan view of a grate embodying my invention. Fig. 1^a is a plan view of the grate with the center bar drawn 45 out; Fig. 2, a transverse section of the bed-plate on line x x, Fig. 1, the grate being 50 omitted; Fig. 3, a transverse section of the bed-plate and grate on line y y; Fig. 4, a sectional detail showing a modified form of side bar and finger; Fig. 5, a detail, to be referred 55 to, made on an enlarged scale; Fig. 6, a sectional detail on line x' x', Fig. 2, looking toward the left; and Fig. 7, a detail to be referred to.

The bed-plate A, preferably cast in one 60 piece, is provided at its front and rear ends with inwardly-extended projections a a', shaped to form bearings for the journals a² a³ of the central section of the grate.

The central section of the grate is made as 65 a single casting composed of longitudinal bars or webs a⁴ a⁵, united at intervals by cross-bars a⁶, leaving central air-spaces a⁷. The longitudinal bars a⁴ a⁵ are made deep, and are provided on their outer side with projections a⁸, 70 with which co-operate fingers b of like side bars or agitators, composed, essentially, of the said fingers and deep longitudinal webs b², provided at their ends with journals b⁴ b⁵, which rest in bearings formed by projections 75 b⁶ b⁷ on the inner side of the front and rear ends of the bed-plate. The fingers b at their junction with the web are of substantially the same width as the said web, and are made tapering toward their points or ends, as shown 80 in Figs. 3 and 4. The deep longitudinal web and the fingers, made wide at their junction with the said web, make a very strong side bar or agitator, and entirely obviates warping and buckling of the said bar. The upper 85 edge of the fingers of the side bars will be rounded or in the arc of a circle, as shown in Figs. 3 and 4, and while I prefer to have the under side of the fingers shaped as shown in Fig. 3, the said under side may be made sub- 90 stantially straight, as shown in Fig. 4. The rear end of the bed-plate is provided with an orifice c, (see Fig. 2,) into which the journal a⁸ of the central section is extended, the upper side or wall of the orifice c crossing the 95 said journal and forming a locking device by which the central section is locked when in operative position, the said central section being prevented from being lifted bodily upward when being operated. Each side bar 100 may be provided with a locking-finger c', (see Figs. 1 and 5,) forming part of the web and

located below and in line with the journal c^2 of the said side bar, and it may be provided with one or more limiting projections c^3 on the back or rear of the web to limit the downward movement of the side bar, the said projection, as herein shown, entering a slot c^4 in the side of the bed-plate. The bearing b^6 is provided with a slot c^5 , (see Fig. 7.) through which the finger c' is passed when the side bar is placed in position, the said finger being located below and out of line with the slot c^5 when the side bar is dropped or turned into its normal position. (Shown in Fig. 1.) Each side bar is preferably provided with a number of short teeth d , leaving air-spaces d' , through which ashes may pass.

The fingers b on the side bars will preferably be located so as to rest upon and be acted upon by the projections a^8 on the central section, as shown by full lines, Fig. 1, thus leaving air-spaces through which air may pass to support combustion, the said air-spaces affording an outlet for ashes and clinkers when the central section is oscillated by a suitable handle, (not shown,) but which is fitted upon the end of the journal a^2 .

The locking-finger c' is so located on the side bars and the slot c^5 so made in the bearing b^6 that the said side bars cannot be displaced or moved vertically by the central section while being oscillated or shaken in the operation of the grate, and can only be removed by hand when the said side bars are turned so that the fingers b stand perpendicular, or substantially at a right angle to their normal operative position. (Shown in Fig. 1.)

By means of the orifice c in the bed-plate the central section is locked against vertical movement without disturbing the lining of the stove, the said central section being readily removable for repairs by drawing it out into the dotted-line position shown in Fig. 1, the journal a^8 being at such time withdrawn from the orifice c .

The longitudinal bars or webs of the central section may be made of any desired depth to obtain strength, and by making the said central section of deep bars provided with

fingers the metal surface near the fire is reduced, the greater portion of the said metal surface being lowered down or away from the fire, thus obviating buckling and warping of the said central section.

By making the upper edge of the fingers of the side bars rounded or in the arc of a circle the coal resting upon the said fingers will drop or roll down onto the central section when the latter is rotated or shaken to agitate the material upon the grate.

I claim—

1. The combination, with the bed-plate provided with a bearing having a slot, as c^5 , of a rocking grate consisting of the central section and side bars, and a locking projection on one or both of said side bars below the journals of the said side bars, the said locking projection being passed through the said slot and located below the bearing of the grate-bar journals out of line with the said slot when the side bar is in operative position and capable of being rocked, substantially as described.

2. The combination, with the bed-plate, of the grate consisting of the central section provided with projections, and independent rocking side bars having fingers co-operating with the projections of the central section, and provided with a limiting projection on its rear side to co-operate with the bed-plate, substantially as described.

3. The herein-described side bar, consisting of the deep longitudinal web b^6 , provided with journals at its ends and with a locking-finger c' , and fingers connected to side of the said web and made at their junction with the web of a depth substantially equal to the width of the web, and having their upper surface made substantially in the arc of a circle, substantially as and for the purpose specified.

In testimony whereof I have signed my name to this specification in the presence of two subscribing witnesses.

GEO: W. WALKER.
